SET OF CHESSMEN

William C. Atkinson, New York, N. Y.

Application October 6, 1955, Serial No. 38,241

Term of patent 14 years

(Cl. D34—5)

Figs. 1, 2, 3, 6, 8 and 9 are front elevational views, respectively, of the king, queen, knight, bishop, castle and pawn in a set of chessmen, showing my new design, Figs. 1 and 8 being shown partly in cross-section;

Fig. 4 is a side elevational view of the knight shown in Fig. 3;

Fig. 5 is a rear elevational view of the knight shown in Fig. 3;

Fig. 7 is a side elevational view of the bishop shown in Fig. 6;

Fig. 10 is a top plan view of the king shown in Fig. 1; and

Fig. 11 is a top plan view of the queen shown in Fig. 2.
I claim:

The ornamental design for a set of chessmen, as shown.
